HONEY PRESS

Reginald D. Bradshaw, Wendell, Idaho, assignor
to R. D. Bradshaw & Sons, Wendell, Idaho, a
copartnership

Application June 11, 1943, Serial No. 490,396

1 Claim. (Cl. 100—50)

1

The invention relates to improvement in honey presses especially adapted for removing honey from cappings removed from honey combs, and has for its primary object the provision of an improved construction of the character indicated which is highly efficient in use.

Other objects will appear hereinafter.

The invention consists of the combinations and arrangements of parts hereinafter described and claimed.

The invention will be best understood by reference to the accompanying drawings forming a part of the specification and in which—

Fig. 1 is a perspective view of a honey press embodying the invention;

Fig. 2 is a top plan view thereof;

Fig. 3 is a side view thereof;

Fig. 4 is a section taken substantially on line 4—4 of Fig. 2; and

Fig. 5 is a section taken substantially on line 5—5 of Fig. 2.

The embodiment of the invention illustrated in the drawings comprises a suitable draining table 10 in the form of a shallow elongated rectangular pan or receptacle arranged in an inclined position and supported at its lower end by supporting members 11 and at its upper end by supporting members 12. The supporting members 12 are extended vertically as shown to constitute the sides 13 of a frame having a cross head or abutment 14 extending across the upper end thereof. A similar cross head 15 is arranged across the lower supports 12 just under the table 10 to furnish stout support therefor. Tie bolts 16 are arranged as indicated adjacent the members 14 and 15 to further secure the frame parts together.

A drain opening 17 is arranged as indicated at the lower end of the table 10 and with which a drain pipe or other means for collecting or removing honey drained from the table 10, is connected. Deflectors 18 are arranged as indicated to deflect drainings from the table 10 to said opening 17.

Combined drain and slide ribs 19 are arranged longitudinally as shown on the top of the table 10 for supporting and facilitating the sliding of press containers 20 thereon. Additional ribs 21 are interspersed between the ribs 19 under the frame 13—14 to furnish further support for the said press containers when they are being subjected to pressure. Suitable side guides 22 are provided on the uprights 13 to facilitate posi-

2

tioning of containers within said frame. A jack screw 23 is arranged as shown to cooperate with the frame 13—14 and a follower 24 is insertable in the tops of the containers 20 for exerting pressure on the comb cappings in said containers, as will be readily understood.

In operation, the operator standing opposite the splash guard 25 removes the cappings from the honey comb in the usual way, depositing the same in one of the containers 20 positioned opposite said splash guard 25. When said container has been thus filled with cappings, the same is shoved along the table towards the upper end thereof and an empty one substituted therefor. This process is repeated until one of the containers is thus brought under the jack screw 23, whereupon a top follower 24 is inserted therein and pressure exerted thereon by means of the jack screw 23, as will be readily understood. A section of cheese cloth is usually placed under the bottom of the container and over the top thereof to facilitate the pressing operation and the subsequent removal of cake from the press container. In this way the retained honey will be readily pressed from the cappings and a cake of wax formed in the container. When the pressing process has been completed, the containers are removed and later opened for the removal of the wax cake therefrom, as will be readily understood. The specific form and arrangement of parts is a simple and effective one for the purpose.

While I have illustrated and described the preferred form of construction for carrying the invention into effect, this is capable of variation and modification without departing from the spirit of the invention. I therefore do not wish to be limited as to the precise details disclosed, but desire to avail myself of such variations and modifications as fall within the scope of the appended claim.

I claim:

A press of the class specified comprising an inclined draining table in the form of a shallow pan having draining means at its lower end and elevated sliding ribs on its top surface to facilitate the sliding of a press container thereon; a press frame arranged over and around the upper end of said table; and a pressing jack cooperating with said frame to compress material in a container resting on said table.

REGINALD D. BRADSHAW.
